UNITED STATES PATENT OFFICE.

JOHN N. THORNTON, OF BRIDGEPORT, CONNECTICUT.

BATH-TUB HEATER.

1,112,038.

Specification of Letters Patent. Patented Sept. 29, 1914.

Application filed September 26, 1913. Serial No. 792,055.

To all whom it may concern:

Be it known that I, JOHN N. THORNTON, a citizen of the United States, residing at Bridgeport, in the county of Fairfield and State of Connecticut, have invented certain new and useful Improvements in Bath-Tub Heaters, of which the following is a specification.

The present invention relates to improvements in bath tub heaters of that type or class which are adapted to be easily connected with or disconnected from the supply pipe of an illuminating fixture in a bath room, and the object of the invention is to provide a simple and inexpensive device of this character which will be durable, and which can be readily positioned for use and adjusted as necessary to uniformly heat the water in the tub.

20 In the accompanying drawings—Figure 1 is an elevation showing a heater constructed in accordance with the present invention in use. Fig. 2 is a detail plan view of the heater. Fig. 3 is a cross sectional view, substantially on the line 3—3 of Fig. 2, on an enlarged scale. Fig. 4 is an enlarged detail longitudinal section of the inlet end of the device.

Referring to the drawings, 1 designates a 30 bath tub which is provided with suitable water supply and waste pipes.

As the heater hereinafter described is adapted for use with tubs of various forms and sizes, the tub and its usual adjuncts are 35 shown more or less conventionally.

The heater, as shown, comprises essentially a tube provided at one end with an inlet adapted to be connected by a flexible pipe 2 with a gas supply pipe 3 and bent upon 40 itself to provide a series of substantially parallel connected members in each of which is formed a plurality of upwardly directed burner outlets. As shown, the tube is bent to provide three parallel members 5, 6 and 45 7, connected as shown and so spaced that the flame issuing from the several outlets 4 will be directed against substantially the entire surface of the bottom of the tub 1 between the feet or supports therefor. As shown, the 50 tube has one end closed by a cap 8 and its other end provided with a tapering nipple 9 over which one end of the flexible tube 2 can be engaged and which is further provided with an inwardly directed extension 55 10 that constitutes the gas inlet of the heater.

In the body of the tube, adjacent the inner end of the part 10, are formed a plurality of air inlets 11.

The heater is supported by legs 12, three being shown. Each leg 12 surrounds the tube forming the body of the heater and is adapted to be turned thereon so that the device may be properly supported and maintained in the desired horizontal relation to the bottom of the tub 1, even if the floor on 65 which it rests is uneven, as indicated in Fig. 3. Set screws 13 are provided for rigidly securing each leg in the desired adjusted position. The adjustment of the legs relatively to the body of the heater above 70 described also enables the distance between the device and the bottom of the tub to be varied, as it will be evident that the tube will be supported at its greatest height and closer to the bottom of the tub when the 75 several legs are in vertical position than when said legs are inclined or turned from the vertical position.

The manner of using and advantages of such a heater will be readily understood and 80 appreciated.

It will be seen that the invention provides a very simple, durable and inexpensive device which can be readily placed in position beneath a tub, or removed, if not desired. 85 By use of such a heater the temperature of water in the tub can be quickly raised and the device is particularly applicable for use at times when the means for heating the water prior to its being introduced into the 90 tub are inoperative.

Having thus described the invention what is claimed and desired to be secured by Letters Patent is:

1. The herein described bath tub heater 95 comprising a tube having a suitable gas inlet and a series of upwardly directed burner outlets, legs embracing the tube and each independently adjustable about the tube to extend therefrom at any desired angle, and 100 means for securing the legs rigidly to the tube in any adjusted position.

2. The herein described bath tub heater comprising a tube having air and gas inlets adjacent one end and bent upon itself to 105 provide a plurality of substantially parallel members each provided with a series of upwardly directed burner openings, a plurality of legs each having a portion surrounding one of said members and adapted to turn 110

thereon to extend at any desired angle from the tube, and means for securing each leg in any adjusted position.

3. The combination with a bath tub, of a
5 heater arranged beneath the tub and comprising a tube having at one end means for attaching a gas supply pipe, said tube being bent upon itself to provide a plurality of laterally spaced connected members, each of
10 which has a series of upwardly directed

burner openings, and legs connected with the tube and bodily adjustable relative thereto for the purposes described.

In testimony whereof I affix my signature in presence of two witnesses.

JOHN N. THORNTON.
